UNITED STATES PATENT OFFICE.

WAHLBORG AHLMGREN, OF NEW YORK, N. Y.

GARMENT-MEASURING APPLIANCE.

1,199,725.

Specification of Letters Patent. Patented Sept. 26, 1916.

Application filed November 30, 1914. Serial No. 874,740.

To all whom it may concern:

Be it known that I, WAHLBORG AHLMGREN, a citizen of Sweden, and resident of the borough of Bronx, in the county of Bronx and State of New York, have invented certain new and useful Improvements in Garment-Measuring Appliances, of which the following is a specification.

This invention appertains to the art of fitting ladies' wearing apparel, and is particularly adapted for the measurement of the skirt or lower portion of various garments, such as gowns, robes, petticoats, mantles, cloaks, wrappers, and the like. For the sake of conciseness, however, the invention will be referred to herein as applicable mainly to the fitting of ladies' dress skirts.

In its concrete form, the invention consists of an improved appliance of the class above mentioned, comprising preferably a wide-meshed net-work of wire constituting a plurality of frames hingedly connected together that are used, first, to locate the line about the hips or waist from which the skirt is to be measured in order to determine its proper length, and subsequently are combined with other elements to decide the height at which the skirt should stand from the ground or floor, to comply with the dictates of fashion, or to meet any special requirement.

Primarily, the invention has for its object to provide an easily operable and comparatively inexpensive garment measuring appliance by means of which a lady can ascertain for herself and to her own satisfaction, if a skirt is of requisite length, or how it may be altered to suit, whether the garment be fashioned by her own hands, or done at home, or merely tried on in view of a conditional purchase, as for instance when a dress is sent from a store to a customer on approbation.

A subsidiary object is to produce an appliance adapted for use exteriorly of the garment when fitted to the person. This feature of the invention has a triple advantage, in that it maintains the appliance in sight of the lady who puts on the skirt for self-measurement, avoids injury to the fabric however delicate it may be, and obviates interference with or from the underclothing while the skirt is being measured on the body of the wearer.

Other objects and advantages will become apparent as the specification proceeds.

With the aforesaid objects in view the invention comprises the improvements and combinations of parts hereinafter described in their preferred embodiments as illustrated in the accompanying drawings, and pointed out in the appended claims.

In the said drawings: Figure 1 is a top plan view of the appliance separate from the garment, but set out and clasped as when placed around the body; Fig. 2 is a fragmentary front elevation, showing the upper part of the appliance, as it appears when positioned over the corresponding portion of the skirt; Fig. 3 is a fragmentary edge view of an annular device used in connection with the appliance after taking the first measurement of the skirt at the hips or waist line; Fig. 4 is a plan view of the said device; Fig. 5 is an end view of the folded appliance minus the said annular device; and Fig. 6 is a full side elevation, illustrating a convenient manner of supporting the skirt on the appliance for the purpose of marking out the correct height thereof at the bottom.

As hereinbefore stated, the appliance includes a number of wire frames, which are jointed to one another so as to constitute an integral entirety. By preference as shown, each frame is composed of one vertical member 11, and two horizontal members 12 and 13, with the exception of either of the front frames, which comprises in addition a second vertical member 14. The length of the vertical members 11 and 14 is determined by the individual height of the lady intending to use the appliance, being so gaged as to indicate the distance from the ground or floor to a line circumscribing the hips in proximity to the waist. In rear the vertical members 11 are somewhat longer than in front in order to allow for the fullness of the back of the body. The horizontal members 12 and 13 meanwhile follow the said line of the hips and the ground or floor line respectively.

The aforesaid wire frames are flexibly interconnected in order that they may be spread out flat, if desired, and thus afford the greatest convenience in manipulating the appliance and adjusting it in position over the skirt to be measured as well as to enable it to occupy the smallest space when stored away. The connections between the several frames are effected, as shown, by forming offsets 15 and 16 at both ends of the vertical members, and providing the contiguous

ends of the horizontal members with eyes 17, 18 engaging the said offsets. This mode of construction not only affords the desired flexibility of joints, but furthermore produces a reliable means of keeping the frames properly aligned and preventing their displacement.

A clasp is provided to hold the meeting edges of the outer frames firmly together, 10 when the appliance is placed around the body and over the skirt, as represented in Fig. 2. The skirt is designated by the reference numeral 19, and indicated by dot-and-dash lines. The said clasp may be of 15 any approved type, and herein is shown as consisting of an inwardly directed offset portion 21, on the middle vertical member 11 of the appliance, adapted for engagement with a slotted plate 22, secured at one end 20 to the adjoining vertical member 14, and thence extending transversely to another vertical member 11, on the right. A plurality of slots 23 are formed in the plate 22, each capable of receiving the offset portion 25 21 of the said middle member, so as to permit varying adjustments of the appliance over the skirt and around the body. A duplicate clasp is provided for the meeting edges of the appliance at the lower end 30 thereof, which is the counterpart of the upper portion of the appliance displayed in Fig. 2.

Braces 25 are employed, preferably to impart a desirable rigidity to the wire frames 35 in a transverse direction. As many such braces may be used as are deemed expedient, but in practice it has been found sufficient to place only one or two in each frame, and to distribute them in staggered 40 relation between alternate frames. An effective method, herein shown, of attaching these braces is to form simple loops or convolutions 26 in the vertical members of the wire frames, and eyes 27 to engage the same 45 at the two ends of each brace. In Fig. 1, for the sake of clearness, the braces 25 are shown as if they were offset inwardly, but in practice they are located substantially in the same plane as the vertical members 50 11, which is the arrangement represented in Figs. 2 and 6.

So far as described, the appliance contains the necessary elements to locate the upper line on the skirt, from which the 55 length of the latter is to be measured, as hereinabove expressed. It is evident that a lady trying on a skirt and surrounding it with the appliance, standing endwise upon the floor and firmly clasped about the body, 60 substantially in the manner delineated in Fig. 2, can very easily and quickly mark out the said upper line on the skirt, by taking a piece of chalk and causing it to follow the series of upper horizontal members 12 of 65 the interconnected wire frames. This may

be done by hand, if need be, but is more accurately accomplished with the aid of a chalk-holder, as 30, which may have lips 31, adapted to embrace loosely the wires 12 on opposite sides, and a jaw 32, to maintain the chalk 33, in suitable position. The upper line having been traced upon the skirt as stated is now a known quantity, and so is the relation thereto of the floor line, which corresponds with the lower edge of the appliance, as will be understood. Therefore, in order to determine precisely the distance at which the skirt will be raised from the floor, when donned for wear, it is merely necessary to adjust its length relatively to 70 the said lower edge of the appliance, and this is best accomplished by removing the garment from the person and operating thereon exteriorly of the appliance, for instance in the manner exemplified in Fig. 6. 85

As illustrated in the figure last named, the appliance is supported upon a standard 35, rising from a pedestal 36, and having radiating arms 37 at its upper end, adapted for engagement with some portion of the 90 wire frames. To this end, the body of the appliance is provided with an intermediate ring 38, which is conveniently lodged within the up-turned ends 39, of the said arms. A plurality of similar rings 38 may 95 be resorted to in order to enhance the rigidity of the appliance at two or more points. as Fig. 6 discloses. The preferred structure of these rings is detailed in Figs. 3 and 4, wherein the same are shown as consisting 100 each of a circular member capable of being parted at one point, and having one end externally threaded, as at 40, while the opposite end is formed into an eye 41. The threaded end 40 is fitted with a detachable 105 hook 42, adapted to be screwed thereon and to engage the eye 41 of the end opposite. This construction enables the ring to be drawn more or less tightly around the appliance and thus operate to maintain it in 110 the exact shape required. Connection between the ring 38 and the appliance may be made in various ways. As shown in Fig. 6, the several rings 38 therein displayed are merely passed through the same 115 loops or convolutions 26 as have been provided for the braces 25, previously described.

For the purpose of inserting the ring 38 through the loops 26 in the vertical members 11, the hook 42 is detached from the screw threaded end of the ring, which is then free to be passed through the several loops in succession, after the manner in which a thread is passed through the eye 125 of a needle. When the screw threaded end of the ring has been passed through all of the loops, the hub of the hook 42 is screwed onto it again, far enough for the hook portion thereof to engage with the eye 41 at 130

the opposite end of the ring. It is obvious that in order to remove the ring a reverse procedure is followed.

One ring 38 is attached to the lower end 5 of the appliance also by means of loops 26 in the vertical wire members thereof, in order to afford a guide for marking the line at which the skirt should stop short of the bottom edge of the appliance, corresponding 10 to the floor line aforesaid. Two or more series of the loops 26 may be located above one another around the said lower end of the appliance, preferably at intervals of one inch or so between each series. The 15 guiding ring 38 can be passed through either or any of the series, and thus will indicate where the chalk is to be applied to denote the height at which the skirt should terminate.

20 In placing the skirt upon the appliance, as represented in Fig. 6, the upper chalk line is made to overlie the horizontal members 12 of the wire frames, to which the skirt may be secured by any suitable fastening means; for example, by ordinary clothes-clamps 44. The waist band of the skirt will then fall within and hang from the upper end of the appliance. The latter it will be observed, could as well be suspended 25 from some primary support located above it, as sustained from below through the instrumentality of a standard after the manner herein illustrated.

30 While I have shown and described the preferred embodiment of my device, it will be understood that changes in the form, arrangement, size, proportions and details thereof, may be made without departing from the scope of the invention as defined 35 by the appended claims.

Having described my invention, what I desire to secure by Letters Patent and claim is:—

1. A garment measuring appliance consisting of a plurality of open parallelogrammic frames flexibly interconnected to permit their being clasped around the body outside the garment for marking a line adjacent the hips, and sufficiently rigid 45 50 55 jointly to enable them to support the garment from the inside when removed from the body for the purpose of laying out a cutting line above the ground, said frames folding one upon another by superimposition so as to lie in parallel planes when collapsed.

2. A garment measuring appliance comprising a number of individually parallelogrammic open frames hingedly connected 60 to one another and forming together a flexible quadrilateral adapted to embrace the body over the garment for tracing a line about the hips, the appliance being capable of insertion inside the garment to support 65 the same removed from the body to allow

it to be marked at the proper level above the ground, said frames admitting of being folded together in a lateral direction so as to collapse in parallel planes one upon another.

3. A garment measuring appliance including a plurality of frames composed of substantially parallel members adapted to collapse flatwise one upon another, said members having intermediate retaining elements 70 and transverse bracing connections engaging the latter, said frames being flexibly attached to one another to enable them to encircle the garment on the body at or near the hips for marking a line therearound, 75 80 and sufficiently rigid conjointly to support the garment on the inside after removal from the body for the purpose of marking the line of cut above the floor.

4. A garment measuring appliance comprising a plurality of substantially parallelogrammic wire frames having eyes intermediate their top and bottom portions, braces parallel with said portions engaging said eyes in staggered relation to one another, said frames being flexibly connected to permit the upper portion thereof to surround the garment on the body for the purpose of laying out a line approximately at the hips, and possessing sufficient rigidity 90 95 to stand apart from the body inside the garment so as to enable the latter to be marked the proper distance from the floor.

5. A garment measuring appliance consisting of open wire frames joined to one 100 another, each of said frames including vertical and horizontal members, offsets formed near the juncture of said members at one side thereof and engagement elements on the opposite side, the elements on one frame 105 engaging the offsets in the adjacent frame, said frames increasing in height in a rearward direction to allow for the fullness of the garment on the body, the arrangement enabling the aggregate frames to be clasped 110 around the body outside the garment for marking substantially the level of the hips, and also to support the garment from the inside after removal from the body for the purpose of determining the proper cutting 115 level from the floor.

6. A garment measuring appliance including a plurality of open wire frames flexibly connected with one another, one frame being composed of two vertical and 120 two horizontal members, the remaining frames having each one vertical and two horizontal members, an engaging element at one side of the latter named frames, and a coöperating device carried by said first 125 named frame and adjustably engageable by said element, said element and said device serving to clasp the frames around the body, the construction being such as to permit the assembled frames to be applied over the 130

garment on the body for tracing a line thereon approximately around the hips, and further to be supported apart from the body inside the garment for the purpose of marking a cutting line above the ground.

7. A garment measuring appliance comprising a plurality of parallelogrammic wire frames having eyes intermediate of their upper and lower ends and flexibly joined together to permit their being adjusted around the body over the garment to trace a line thereon in proximity to the hips, one or more braces insertible through said

eyes, and a hook and eye adjusting device for each brace imparting rigidity to the aggregate frames in order to support them inside the garment when removed from the body for the purpose of outlining the proper trimming level above the ground.

Signed at the borough of Manhattan in the county of New York and State of New York this 28th day of November A. D. 1914.

WAHLBORG AHLMGREN.
